DOOR STRUCTURE

Arthur A. Van Atta, Marion, Ohio

Application April 20, 1936, Serial No. 75,469

13 Claims. (Cl. 189—46)

This invention relates to a door structure of the hinged adjustable type, capable of being fitted as a screen or other type of door, but it is designed primarily for use as a screen door.

5 The object of the invention is to provide, in a manner as hereinafter set forth, a hinged adjustable door structure capable of being adjusted to compensate for different widths and heights of door openings.

10 A further object of the invention is to provide, in a manner as hereinafter set forth, a door structure of the class referred to including a hinge unit and an adjustable door unit, and with said units having coacting means to provide for the adjusting of the door unit to compensate for door openings of different widths and for maintaining the door unit in its adjusted position.

15 A further object of the invention is to provide, in a manner as hereinafter set forth, a door structure of the class referred to including a hinge unit and a door unit and with said units having coacting means to provide for adjusting the length of said units to compensate for door openings of different heights.

20 Further objects of the invention are to provide, in a manner as hereinafter set forth, a door structure of the hinged adjustable type which is simple in its construction and arrangement, 30 strong, durable, compact, quickly adjusted and detachably secured in its adjusted position, readily installed with respect to a door opening, thoroughly efficient in its use and comparatively inexpensive to manufacture.

25 With the foregoing and other objects in view, the invention consists of the novel construction, combination and arrangement of parts as will be more specifically described and as are illustrated in the accompanying drawings wherein is 35 shown an embodiment of the invention, but it is to be understood that changes, variations and modifications may be resorted to which fall within the scope of the invention as claimed.

In the drawings:

40 Figure 1 is a front elevation of the hinged adjustable door structure, in accordance with this invention, in the form of a screen door structure,

45 Figure 2 is a rear elevation of the structure shown in Figure 1,

50 Figure 3 is a side elevation of the form of screen retaining side strips employed,

55 Figure 4 is a side elevation of the form of screen retaining end strips employed,

Figure 5 is a front elevation of a panel for

connection to one of the units or sections of the door,

Figure 6 is a vertical sectional view of the panel,

Figure 7 is a front elevation of the hinged unit 5 of the door,

Figure 8 is a front elevation of the adjustable unit of the door,

Figure 9 is a front elevation of the adjustable extension panel for the adjustable unit, 10

Figure 10 is a rear elevation of the adjustable unit,

Figure 11 is a section on line 11—11 Figure 1, 15

Figures 12 and 13 are respectively sections on

lines 12—12 and 13—13 Figure 1,

Figure 14 is a fragmentary view in perspective of the upper portions of the units of the door body disassembled,

Figure 15 is a perspective view of the bottom member or bottom plate of the adjustable unit, 20

Figure 16 is a perspective view of the adjustable extension panel of the adjustable unit,

Figure 17 is a section on line 17—17 Figure 7,

Figure 18 is a section on line 18—18 Figure 8,

Figure 19 is a section on line 19—19 Figure 8, 25

Figure 20 is an elevation of the form of reinforcement employed for the ends of the adjustable extension panel,

Figure 21 is a section on line 21—21 Figure 9, 30

and

Figure 22 is a section on line 22—22 Figure 9.

The hinged adjustable door structure includes an outer or hinge unit 20 and a rear or door unit 21 which is mounted for lateral shifting relative to the inner face of, as well as being permanently 35 extended from one side of unit 20.

The unit 20 includes a channel member 22 which opens inwardly. The member 22 consists of a front 23 and a side 24 bent upon itself to provide a fold 25 on the outer face of side 24. 40

The member 22 includes a side 26 which is of a length to terminate adjacent each end of front 23. The side 26 is bent upon itself to provide a bead 27. Spaced superposed hinges 28, 29, and 30, indicated in dotted lines in Figures 1 and 7 are 45

anchored to and extend laterally from the side 24 of the member 22. The front of member 22 intermediate its ends is formed with a transverse slot 32. The front 23 of member 22 in proximity to its lower end is formed with a transverse slot 50

33. A short channel iron 34, which opens outwardly is secured transversely of the outer face of front 23 of member 22 and is formed with a lengthwise extending slot 35 which registers with the slot 32. A tapered outwardly opening chan- 55

neled shaped bar 36 is secured transversely of the outer face of member 22, is of a length to extend laterally with respect to the side 26 of member 22 and constitutes an upper hanger. The bar 36 is arranged in proximity to the upper end of member 22 and is formed at its free end terminal portion with a lengthwise extending slot 37. The bar 36 at its fixed end terminal portion has mounted therein an inwardly extending pin 38. Secured transversely of the outer face of the member 22 in proximity to its lower end is tapered outwardly opening channeled shaped bar 39 which is of a length to extend laterally from member 22, is disposed in parallelism with respect to bar 36 and constitutes a lower hanger. The bar 39 at its free end terminal portion is formed lengthwise thereof with a slot 40 and at its fixed end terminal portion has mounted therein an inwardly extending pin 41. The pins 38 and 41 extend through the front 23 of the member 22 and are arranged in proximity to the edge 42 of member 22. The positioning of the ends of the side 26 of member 22 adjacent the ends of the front 23 of member 22 provides clearances for a purpose to be referred to.

The unit 21 includes a side member 43 of angle-shape cross section to provide the flanges 44, 45 disposed at right angles to each other and with the flange 44 depending below the flange 45. The flange 44 is what may be termed a front flange and flange 45 a rear flange. The flange 45 extends rearwardly from the inner side edge of the flange 44 whereby flange 45 is inset with respect to the outer edge 46 of flange 44. That part of flange 44 which depends from the lower end of flange 45 is indicated at 47. The upper edge of member 43 constitutes a seat. The cross sectional length of the flange 44 is greater than that of the flange 45. The outer end edge of flange 45 is inturned to provide a bead as indicated at 48. The unit 21 includes a rearwardly opening channel-shaped side member 49 having its front designated at 50 and its inner and outer sides indicated at 51, 52 respectively. The side 52 is bent inwardly upon itself to make it of double thickness and to form an inwardly extending flange 53. The side 51 is bent outwardly upon itself to provide a bead 54. The side 51 of the member 49 is of less length than the side 52. The upper and lower ends of the side 51 are spaced from the ends of the front 50. The side 51 of the member 49 is of less length than the flange 47 of member 53, but corresponds in length to the length of the flange 45 of member 43. The side 51 is arranged in spaced parallel relation to the flange 45 of the member 43. Seated upon the top of side 43 and also upon the top of the side 51 is a horizontally disposed rearwardly opening channel-shaped member 55 which has one end flush with the edge 46 of flange 44. The lower flange 56 of member 55 is bent upon itself to provide a bead 57. The member 55 abuts the inner face of the side 52 of member 49 and also abuts the rear face of the front 50 of member 49. The member 55 carries a pin 58 which extends through an opening 59 in the upper end of the member 49. The member 55 is formed with a slot 60 disposed lengthwise thereof. The unit 21 includes a bottom plate 61 which abuts the inner face of the side 52 of member 49 and also abuts the lower portion 61 of the flange 44. The plate 61 is formed with horizontally and vertically disposed slots 62, 63, respectively, arranged in spaced relation and disposed at right angles to each other. The plate 61 has its top formed with a rearwardly directed

right angularly disposed flange 64 having its free end inturned to provide a bead 65. Flange 64 has spaced openings 66. The plate 61 is bent upon itself as at 67 to provide a fold on the lower portion of its inner face.

The parts of the unit 20 are suitably secured together by welding or otherwise. The parts of the unit 21 are suitably secured together by welding or otherwise.

When the elements 20 and 21 are mounted in the manner as shown, the element 21 may be shifted laterally relative to the element 20 to compensate for the different widths of door openings.

A web of reticulated material, such as screen wire is indicated at 68 and which has its upper and lower end marginal portions bent to seat upon the upper face of the flange 56 of member 55 and against the lower face of the flange 64 of plate 61. The side marginal portions of the web 20 68 are bent to oppose the outer and inner side faces respectively of the flange 45 and the side 51 of the member 49. Retaining strips 69 are arranged against the bent end marginal portions of the web 68 and retaining strips 70 are positioned against the bent side marginal portions of the web 68. The strips 69 and 70, as well as the side 51 of the flange 45 are apertured. The apertures in the strips 69, 70 are aligned with the apertures in the side 51 of flange 45. Extending through the registering apertures and also through the bent marginal portions of the web 68 are holdfast means 71 which anchor the bent marginal portions of the web 68, the strips 69, 70 and the flange 45 and side 51 together or, in other words, the web 68 is anchored to the unit 21 and provides a screened door section. The web 68 constitutes a panel.

The lower portion of the member 49 is offset as at 72. The lower portion of the member 22 is offset as at 73.

There is associated with the units 20 and 21 a means or unit for increasing the length thereof when desired and the said means includes a rectangular panel or plate 74 having its top edge 45 formed with a segmental extension 75. The panel 74 intermediate its ends is formed with a slot 76 disposed lengthwise thereof. Mounted on each end of the panel 74 is a slidably end piece 77 consisting of a plate 78 having a flange 79 at its bottom bearing against and extending inwardly at right angles to the bottom edge of panel 74. One side marginal portion of the end piece is designated 80. The top marginal portion of the end piece is designated 81. The marginal portion 80 has its top edge arranged below the top edge of marginal portion 81. The upper end of marginal portion 80 has a lateral lug 80^a which is bent against the inner face of portion 80. The marginal portions 80, 81 are bent to oppose the rear face of plate 78. The lug 80^a bears against the rear face of plate 78. The marginal portions 80, 81 overlap an end edge and a part of a top edge of panel 74. One of the end pieces is arranged in the offset portion 73 of the member 22. Extending through the slot 63 of plate 61 and the slot 76 of panel 74 is a bolt and nut connection 82 which provides for the panel 76 and an end piece 77 to bodily move with the adjustable unit 21 when the latter is shifted relatively to the hinge unit 20 to increase or decrease the width of the door to compensate for different widths of door openings. The nut and bolt connection 82 also provides for travelling in the slot 63 when the panel 74 is lowered to increase the length of the 75

door. When the panel 74 is lowered the end pieces 77 are carried therewith. The flanges 79 of the end pieces 77, when the door is in normal position abut the lower ends of the members 22 and 49, but when the panel 74 is lowered or vertically adjusted to increase the length of the door, the flanges are spaced from the lower ends of the members 22 and 49. The panel 74 carries the end pieces therewith when the panel is lowered or vertically adjusted.

The door includes a front and a rear handle indicated 83, 84 respectively. The end 85 of handle 84 is fixed to the flange 44. One end of the handle 83 is pivotally mounted on a bolt 86 which is slidably mounted in the slots 32, 35. The other end of the handle member 83 merges as at 87, in a coupling piece 88 secured to the front face of member 49. The coupling piece is arranged below the slots 33, 35. The handle 84 has its other end merge, as at 89 in a coupling piece 88. The member 83, 84 extends at a downward inclination from bolt 86 to member 49.

The hinges which will be used in connection with the hinge unit, preferably will be of the spring controlled type.

The unit 21 when set up forms what may be termed a rectangular frame having its bottom portion of materially greater length than that of its top portion. The width of the side portions of unit 21 is materially less than the length of the bottom portion thereof.

In lieu of using the reticulated web 68 to close the frame-like adjustable unit 21, the unit may be closed by a panel consisting of a frame carrying 35 a foraminous, transparent or translucent member and such panel is shown by way of example as a reticulated one, Figures 5 and 6. The panel is generally indicated at 91 and it includes a rectangular frame 92 closed by a strip of screen cloth 40 93. The panel 91 is to be positioned to oppose the flanges 45, 47, 64 and side 51. The panel 91 is to be suitably secured to the adjustable unit 21.

The hinges 28, 29, 30 have their outer leaves anchored against a wall, formed with a door opening, at spaced points of that portion of said wall bordering one side of said opening.

The unit 29 is termed a hinged outer unit. The unit 21 is termed a bodily adjustable inner unit. The plate 74 and the end pieces mounted thereon 50 constitute what is termed a lower extension unit.

What I claim is:

1. An adjustable door structure comprising a bodily adjustable inner unit, an outer unit adapted to be hinged to a support having a door opening and including superposed means for extension across the door opening in spaced relation to the support, said inner unit arranged rearwardly of the outer unit for closing the door opening, said units having oppositely disposed spaced coacting means to permit the bodily adjusting of the inner unit relative to the outer unit and for detachably securing the inner unit in its adjusted position against the rear of the outer unit.

2. An adjustable door structure comprising a bodily adjustable inner unit, an outer unit adapted to be hinged to a support having a door opening and including superposed means for extension across the door opening in spaced relation in respect to the support, said inner unit arranged rearwardly of the outer unit for closing the door opening, said units having oppositely disposed spaced coacting means to permit the bodily adjusting of the inner unit relative to the outer unit and for detachably securing the inner unit in its adjusted position against the rear of the outer

unit, and front and rear handle means extending across the front and rear of the inner unit, said handle means being slidably connected at one end to one of said units and attached at its other end to the front and rear of the other of said 5 units.

3. An adjustable door structure comprising a bodily adjustable inner unit, an outer unit adapted to be hinged to a support having a door opening and including superposed means for extension across the door opening in spaced relation to the support, said inner unit arranged rearwardly of the outer unit for closing the door opening, said units having oppositely disposed spaced coacting means to permit the bodily adjusting of the inner 10 unit relative to the outer unit and for detachably securing the inner unit in its adjusted position against the rear of the outer unit, and a unit corresponding in width to that of the inner unit for adjusting the length of and slidably mounted 15 in the lower ends of the outer and inner units, the length adjusting and inner units having coacting means to provide for the former moving with the inner unit when the latter is laterally adjusted, said length adjusting and inner units 20 having coacting means to permit of the extension of the length adjusting unit from the lower ends of the outer and inner units and for detachably securing the length adjusting unit in its extended position. 30

4. In an adjustable door structure, a hinged unit, a bodily adjustable unit for adjusting the width of the door structure positioned against one face of and substantially of the same height as the hinged unit, a lower unit for adjusting the 35 length of the door structure arranged within the lower portion of the said other units and bodily carried with the adjustable unit, and a series of superposed means for respectively slidably suspending the adjustable unit from the hinged unit, 40 for connecting the lower unit to the adjustable unit and for detachably securing the adjustable and lower units in adjusted position.

5. In an adjustable door structure, a hinged unit, a bodily adjustable unit for adjusting the 45 width of the door structure positioned against one face of and substantially of the same height as the hinged unit, a lower unit for adjusting the length of the door structure arranged within the lower portion of the said other units, means for 50 slidably suspending the adjustable unit from the hinged unit, for connecting the lower unit to the adjustable unit and for detachably securing the adjustable and lower units in adjusted position, and handle means for said structure slidably connected at one end to said hinged unit and attached at its other end to said bodily adjustable section. 55

6. An adjustable hinged door structure comprising a bodily adjustable inner and an outer 60 unit substantially the same height, said outer unit including spaced hinged means, each having a leaf adapted to be anchored to a side wall forming means of a door opening, said hinged unit including upper and lower hangers disposed 65 transversely of the front face of the inner unit, and said units having spaced coacting superposed means adjacent each side thereof and coacting with said hangers to provide for the bodily adjusting laterally of the inner unit relative to the 70 outer unit and for detachably securing the inner unit in its adjusted position.

7. An adjustable hinged door structure comprising a bodily adjustable inner and a hinged outer unit substantially the same height, said 75

outer unit including spaced hinged means, each having a leaf adapted to be anchored to a side wall forming means of a door opening, said hinged unit including upper and lower hangers disposed transversely of the front face of the inner unit, said units having spaced coacting superposed means adjacent each side thereof and coacting with said hangers to provide for the bodily adjusting laterally of the inner unit relative to the outer unit and for detachably securing the inner unit in its adjusted position, and adjustable means slidably engaging in said units, slidably connected to said inner unit and extendible from said units for increasing the length of said units.

8. In a hinged adjustable door structure, front and rear units arranged in facewise opposed relation, said front unit including superposed hinge means having leaves extended from one side thereof for securing to a support to connect said front unit to the latter, the said front unit having inwardly extending means at the said side thereof for spacing it from the support, the inner one of said units being of rectangular contour and having one side thereof permanently opposing the said inwardly extending means, said units having superposed spaced aligning oppositely disposed means to provide respectively for slidably connecting the said inner unit against and throughout the inner face of the front unit, for laterally adjusting the inner unit relative to the front unit and for detachably anchoring the inner unit to the front unit.

9. In a hinged adjustable door structure, front and rear units arranged in facewise opposed relation, said front unit including superposed hinge means having leaves extended from one side thereof for securing to a support to connect the front unit to the latter, the said front unit having inwardly extending means at the said side thereof for spacing it from the support, the inner one of said units being of rectangular contour and having one side thereof permanently opposing the said inwardly extending means, said units having superposed spaced aligning oppositely disposed means to provide respectively for slidably connecting the said inner unit against and throughout the inner face of the front unit, for laterally adjusting the inner unit relative to the front units and for detachably anchoring the inner unit to the front unit, and a lengthwise extension unit common to the lower portions of, and slidably engaging in the said other units, said extension and rear units having coacting means for slidably connecting and detachably anchoring the extension unit to the rear unit.

10. In an adjustable door structure, a laterally adjustable rectangular inner unit, an outer unit opposing the front face of the inner unit and having means for hinging one side thereof to a support, said units having spaced laterally aligned superposed oppositely disposed coacting means to permit the bodily adjusting laterally of the inner unit relative to the outer unit to vary the width of the door structure and for detachably securing the inner unit in its adjusted position, an extension unit at the lower portions of the said other units and capable of being shifted laterally relative to the outer unit and vertically relative to the outer and inner units to vary the length, while maintaining the width, of the door structure, said inner and extension units having coacting means to provide for the shifting laterally of the extension unit in unison with the inner unit, and said extension and inner units having coacting means to permit the extension unit

being vertically adjusted relative to the lower ends of the outer and inner units and for detachably securing the extension unit in its vertically adjusted position.

11. In an adjustable door structure, a laterally adjustable rectangular inner unit, an outer unit opposing the front face of the inner unit and having means for hinging one side thereof to a support, said units having aligned superposed oppositely disposed co-acting means to permit the bodily adjusting laterally of the inner unit relative to the outer unit to vary the width of the door structure and for detachably securing the inner unit in its adjusted position, front and rear handle means, said rear handle means disposed across the rear face of and having its end terminal portions fixed to the sides of said inner unit, and the front handle means disposed across the front of the outer and rear units and having one end terminal portion fixed to one side of the rear unit and its other end terminal portion slidably connected to one side of the outer unit, that part of each of said handle means, other than the end terminal portions of the latter being diagonally disposed and offset relative to the outer and inner units.

12. In an adjustable door structure, an outer unit including an inwardly opening channel member having fixedly secured thereto and extending from the inner side thereof spaced bars, each formed with a slot, said member being formed with spaced openings, an inner unit of frame-like contour positioned against the rear face of the outer unit, said inner unit having spaced aligning slots adjacent one side edge thereof positioned to oppose the inner face of and the openings in said member, said inner unit being formed with openings adjacent the other side edge thereof, said bars arranged relatively to said inner unit to have their slots oppose the outer face of one side portion of and the openings in the inner unit, releasable means extending through the openings in said member and the slots of the inner unit for connecting said units together, releasable means extending through the slots of said bars and the openings of the inner unit for connecting said units together, the said releasable means and slots providing for the laterally adjusting of the inner section relative to the outer section, and the said releasable means providing for anchoring the rear unit in its adjusted position.

13. In an adjustable door structure, an outer unit including an inwardly opening channel member having fixedly secured thereto and extending from the inner side thereof spaced bars, each formed with a slot, said member being formed with spaced openings, an inner unit of frame-like contour positioned against the rear face of the outer unit, said inner unit having spaced aligning slots adjacent one side edge thereof positioned to oppose the inner face of and the openings in said member, said inner unit being formed with openings adjacent the other side edge thereof, said bars arranged relatively to said inner unit to have their slots oppose the outer face of one side portion of and the openings in the inner unit, releasable means extending through the openings in said member and the slots of the inner unit for connecting said units together, releasable means extending through the slots of said bars and the openings of the inner unit for connecting said units together, the said releasable means and slots providing for the laterally adjusting of the inner unit.

section relative to the outer section, the said releasable means providing for anchoring the rear unit in its adjusted position, the front of said member and the said side portion having corresponding end terminal parts outset, a length adjusting unit disposed across a part of the lower portion of the inner element and extending into the said outset parts, and said inner and length adjusting units having registering slots disposed

in angular relation and means extending through such slots to provide for adjusting the length adjusting unit relative to the other units, for detachably securing the length adjusting unit in adjusted position and for the length adjusting unit being carried with the inner unit on the adjusting of said inner unit. 5

ARTHUR A. VAN ATTA.
